UNITED STATES PATENT OFFICE

2,199,101

BUS BODY

Earl M. Hicks, Lebanon, Ind.

Application June 29, 1939, Serial No. 281,836

1 Claim. (Cl. 296—137)

In my Patent No. 2,104,989 issued January 11, 1938, there is disclosed a metallic bus body structure having metal arched roof plates supported by longitudinally spaced inverted U-shaped bows, 5 wherein the arched roof plates are so attached to and supported by inverted U-shaped bows that, as the vehicle passes over an uneven terrain, the bows and roof plates may flex and shift relative to each other without damage and without 10 variation of the desired weatherproof characteristics of the structure.

In that structure the arched portions of the roof supporting bows are exposed as transverse ribs depending below the under-surfaces of the 15 roof plates.

The object of my present invention is to provide means by which flat metal ceiling plates may be associated with the under-surfaces of the arches of the roof supporting bows, to provide 20 a substantially smooth arched ceiling for the bus body in such manner that said ceiling plates will not interfere with the desired flexibility between the bows and roof plates, without the utilization of fastening members of such 25 character that they might possibly loosen and become exposed below the under-surfaces of the ceiling plates in such manner as to injure the passengers.

The accompanying drawings illustrate my invention.

Fig. 1 is a medial longitudinal section through one of the intermediate bows, and one of the end bows, together with the roofing plates and my improved ceiling plates.

Fig. 2 is an enlarged transverse section through one of the supporting bows and showing the ceiling plate construction.

In the drawings 10 indicates an intermediate bow of channel shape with an outwardly presented mouth, flanked at each side by laterally extending flanges 11. 12 indicates an end post. Supported upon the end posts 12 and flange 11 of the first bow 10 is a roof shell 13 which, at its inner end, is provided with a depending flange 14 which enters the open mouth of the first bow. A sound deadening and heat insulating shell 15 lines the inner-surface of shell 13 with its inner edge interposed between shell 13 and the under-lying flange 11 of the bow 10. Extending between adjacent bows are arched sheet metal roofing plates 16 provided, at each transverse edge, with depending flanges 17 which lie within the open mouths of the supporting bows. Heat insulating and sound deadening

sheet 18 is interposed between each roof plate 16 and the supporting arches of the bows.

At the springs in the arches of the bows, the bows and the tops of the end posts are connected by horizontal runners 19 and the roof plates 16 extend down to these runners, the depending ends of the roof plates being firmly attached to these runners and to the bows at the springs of the arches only.

Thus far, the structure is as disclosed in my 10 above-mentioned patent.

The intermediate ceiling plates 20 have one edge 21 laterally offset from the main body of the sheet the thickness of a sound deadening sheet 22 and at the other edge 23 laterally offset the thickness of the sound deadening sheet 22 plus the thickness of the sheet 20. The sheets 20, with their laterally offset edges are normally flat, that is, unarched, until assembled in the structure.

Mating with the under-surface of each bow 10, from spring to spring of the arch thereof, is an arched sheet metal retainer 30 formed at one edge into an outstanding flange 31 and at the opposite edge doubled back inwardly upon itself, as indicated at 32, to form a pocket 33 capable of receiving the laterally offset edge 21 of the ceiling plate. The retaining strip 30 is so associated with the arched portion of the bow 10 as to leave a space 34 between itself and the bow, and open along the doubled edge of the retainer to afford a space for the reception of the laterally offset edge 23 of a ceiling plate.

Each intermediate bow 10, at one side, is provided with a retainer 30 which is anchored at 35 its ends, at the springs of the arches, to the bow or to the longitudinal runner with the throats of pocket 33 all fastening in the same direction. These arched retainers 30 are also desirably, though not necessarily, attached to 40 their adjacent bows at intermediate points between the springs of the arches, conveniently by spot welding.

In assembling the ceiling plates, an arched retainer 30 is associated with an end bow 10. 45 A ceiling plate 20 is then flexed to arched form, overlaid by a deadening sheet 22, its edge 21 inserted into the pocket 33 of the retainer 30 and its edge 23 brought into engagement with the under-surface of the arch of the next bow 50 10. Thereupon another arched retainer 30 is associated with that bow 10 and anchored at its ends at the springs of the arches and at intermediate points by spot welding, if desired, the pocketed edge of the retainer underlying the 55
